UNITED STATES PATENT OFFICE.

THOMAS C. BROWNE, OF NEW YORK, N. Y.

PORTABLE SHELF AND RACK DEVICE.

Application filed September 4, 1926. Serial No. 133,541.

This invention relates generally to portable shelf and rack devices, the invention having more particular reference to a novel type of portable shelf and rack device adapted for use when bathing infants and children, and which may be placed in a corner of the room, or collapsed when not in use. The invention has for an object the provision of a device of the class described embodying improved and novel features of construction and arrangements of parts.

For further comprehension of the invention, and of the objects and advantages thereof, reference will be had to the following description and accompanying drawing, and to the appended claims in which the various novel features of the invention are more particularly set forth.

Fig. 1 of the drawing is a front perspective view of my improved device.

Fig. 2 is a similar view showing the shelves removed therefrom.

Fig. 3 is an enlarged sectional view taken on the line 3—3 of Fig. 1.

Fig. 4 is a similar view taken on the line 4—4 of Fig. 1.

Fig. 5 is an enlarged sectional view taken on the line 5—5 of Fig. 1.

As here embodied my improved portable shelf and rack device comprises upright members 10 and 11, hinged as at 12, and provided with upper shelf supports 13 and 14, of angle shaped construction, adapted to slidably receive the shelf proper 15, which is 30 slidably engaged in the upper shelf supports 13. The shelf proper 15, is provided with three sides, two of which are formed at right angles, so as to extend the upright members 10 and 11 at right angles, so as to permit my 40 improved device to be placed in a corner of the room. The front edge of the shelf proper 15 is preferably formed with a curve, so as to add to the decorative appearance of my improved device. The upper shelf 45 supports 13 are pivotally attached at their forward ends, as at 16, by a pin, or the like, to the upright members 10 and 11, and are provided with extended members 17, adapted to engage in apertures 18, formed in the up-

right members 10 and 11, as a means of supporting the shelf proper 15, in a horizontal or declined position, the latter being such as will prevent articles placed therein from rolling or falling on the floor.

Additional shelves proper 19 and 20, similar to the above described shelf are similarly

removably attached to the shelf supports 21 and 22 which are rigidly attached to the upright members 10 and 11, so as to support the said shelves in a horizontal position.

The clips 23 are attached at one extremity, as at 24, to the said shelf supports, and are provided with a free extremity 24', bent so as to engage in notches 25 formed in the said shelves proper, so as to hold the said shelves proper in place in the said shelf supports.

The said shelves proper are provided with apertures 26, formed or cut therein, adapted to support an eye dropper, cylindrical containers, brush holders, and the like, not shown in the accompanying drawing. Similar apertures may be provided to support bottles 27, containing medicine, infants' toilet necessities, and the like.

The receptacle 28 is removably attached to the upright member 11, by clips 29, attached to and extended from the said upright member 11, and adapted to engage the receptacle 28. The shelf proper 20, which is positioned directly above the receptacle 28, is provided with an aperture 30, located therein, so as to permit soiled clothes, towels, and the like, to be placed in the said receptacle.

A clothes hanger, or towel bars, adapted to support clothes, towels, wash cloths, and the like, comprising a bar 31 hinged, to the support 33, and extended therefrom, having its extended extremity formed or bent ring shaped, as at 32, so as to engage wash basin, wash dish, or the like. The bars 34, are similarly hinged to the support 33 and extended therefrom. The support 33 is attached to the upright member 11, the above described construction being such as will permit the said bars to be extended from the upright member 11, as clearly shown in Fig. 2, when in use, or folded against the said upright member, when not in use as clearly shown in Fig. 1.

The rack supports 35, are hinged as at 35', to the upper edges of the upright members 10 and 11, and extend the entire width of the said upright members. The rack pins 36, are attached to the rack supports, and extended therefrom, and are provided with enlarged extremities 37, of spherical construction, provided with axial apertures 38, or openings. The rack supports 35, are provided with notches 39, so as to permit the rack supports 35 to engage in the handle element 40, and rest on or be supported by the handle brackets 41 and 42, when the

said rack supports 35, are in a horizontal position, as clearly shown in Fig. 2, which will permit pins, similar miscellaneous articles, and the like, to be placed in the apertures 38, and which will permit my improved device to be placed compactly in the corner of a room. It being understood, that clothes, and the like, may be hung on the rack pins 36, when the rack supports 35, are in a horizontal or vertical position, the latter shown in Fig. 1.

The handle element 40 is of U shaped construction, having parallel extended elements 43 and 44, the extended element 43 is 15 adapted to slidably engage in the handle bracket 41, attached to the upright member 11, and is provided with an aperture adapted to receive the said extended element 43. The extended element 44 is adapted to engage in 20 the locking member 45, through the opening 46, when the said locking member is pivotally positioned in the handle bracket 41, so as to have its opening 46 in line with a similar opening 47 formed in the handle bracket 25 41. The locking member 45 is pivotally, or rotatively mounted in an aperture formed in the handle bracket 41, and is provided with an extended element 48, handle, or the like. The latter described construction being 30 such as will removably engage the handle member 40, so as to permit my improved device to be lifted and carried as may be desired. The extended element 44 having its extremity, formed or bent at right angles thereto, as at 49, so as to secure the engagement 35 of the handle member 40.

While I have above described the preferred form, construction and arrangement of the several elements employed, it will be 40 understood that the device is nevertheless, susceptible of considerable modification therein, and I therefore reserve the privilege of resorting to all such changes as may be fairly embodied within the spirit and 45 scope of the invention as claimed.

Having thus described my invention, what I claim as new and desire to protect by Letters Patent of the United States is as follows:

50 1. In a device of the class described, an

upright member hinged to a second upright member, said upright members being provided with upper shelf supports adapted to slidably receive a shelf proper, said upper shelf proper being provided with three sides, 55 two of the said sides being formed at right angles, so as to extend the said upright members at right angles, said upper shelf supports being pivotally attached to the said upright members, and said upper shelf supports being provided with extended members adapted to engage in apertures formed in the said upright members, as a means of holding the upper shelf proper in a horizontal or depressed position. 60

2. A cabinet comprising vertical side members, hinges attached to adjacent edges of said side members for pivotally connecting the latter together, shelf supports comprising grooved members pivotally mounted 70 at one extremity on said side members near the unattached edges thereof and having an opening in the other extremity thereof, a shelf having edge portions adapted to engage in the grooves of said shelf support, said side members being provided with spaced openings adapted to register with the openings in the ends of said shelf supports, and removable pins adapted to be inserted 75 through the openings in said shelf supports and into any desired openings of said side members for retaining said shelf supports and the shelf mounted thereon at a suitable inclination. 80

3. A cabinet comprising vertical side members attached together, along adjacent edges, shelf supports pivotally mounted at their outer ends on said vertical side members and having openings in their other ends, spaced openings in said side members adapted to register with the openings of said shelf supports, a shelf mounted on said shelf supports, and a pin adapted to be inserted 90 through the opening in said shelf supports and into the openings of said side members for retaining said supports and the shelf thereon at a desired inclination. 95

In testimony whereof I have affixed my signature.

THOMAS C. BROWNE.
